[57] ABSTRACT

A trash container compactor, which is adaptable to most common trash containers, provides a feature which produces a crushing force capable of increasing the storage capacity of a container by a factor several times its normal capacity, depending upon the type of refuse within the container. The compactor also provides the option of using a simple tamping method to increase the container volume intermittently, as refuse is inserted, when high compression is not a requirement.

SHEET 1 OF 2

TRASH CONTAINER COMPACTOR

BACKGROUND OF THE INVENTION

My present invention relates generally to most common commercial trash containers in which an accumulation of refuse requires the compacting of a loose volume of material for the purposes of providing the utilization of the complete volume available, resulting in a corresponding reduction in the number of containers required for refuse accumulation.

Households, apartments, restaurants, and commercial buildings all have similar problems involving the accumulation of refuse (i.e. garbage, cardboard cartons, rags, plant clippings, etc.) requiring that a sufficient quantity of trash containers be made available for the proper disposal of the refuse. The size of the storage areas for these containers has been a consistent problem to the foregoing establishments and many times this space deficiency has limited the quantity of containers which may be stored.

The efficiency of the refuse collectors is handicapped by the number of containers that are handled for each establishment, resulting in added costs or taxes for the owners and taxpayers. The storage capacities of the refuse trucks are limited by trash which is loosely deposited in each container. Loosely deposited garbage is prey for rodents, dogs, and cats and is easily removed from any loosely filled container. Compacting trash within a container by the hands or feet is awkward, dangerous and very limited in obtaining desired results.

The state of the art in the design of a simple and effective method for compacting refuse is seriously lacking and requires added stimulus to provide the public with a means of supporting the ecological problems with which we are faced today. This invention fulfills the initial requirement for improving the existing state of the art by reducing the volume of accumulated refuse.

SUMMARY OF THE INVENTION

Briefly, my invention is preferably accomplished by providing a tamping plate, or press, attached to a vertical post from which supports extend radially outward from the post in which a manner as to adequately stabilize and strengthen the structure. At the top of the post a horizontal tube is attached, and a free rotational shaft, which contains a crank assembly on one end, extends laterally outward from both ends of the horizontal tube of the post assembly. Cables are attached to both ends of the shaft assembly so as to form a winch. Quick release hooks are mounted to both ends of the cables for fastening to the shaft and to the handles of the trash container. By turning the crank the cables are wound around the shaft thereby moving the tamping plate against the refuse with sufficient crushing force capable of compacting the trash to its minimum volume.

BRIEF DESCRIPTION OF THE DRAWING

My invention will be more fully understood and other features and advantages thereof will become apparent from the description given below of certain exemplary embodiments of the invention. This description of the exemplary embodiments is to be taken in conjunction with the accompanying drawing in which:

FIG. 1 is a front elevation of the trash container compactor, including the winch assembly, having a structure or configuration in accordance with this invention;

FIG. 2 is a top view of the trash container compactor showing the structure or configuration of the base;

FIG. 3 is a fragmentary side view of the compactor having a structure or configuration in accordance with this invention;

FIG. 4 is a front elevation view, of smaller scale, showing the compactor in position with base firmly positioned against the trash of a standard trash container;

FIG. 5 is a front elevation, of smaller scale, showing the compactor with the winch assembly removed and with the base firmly positioned against a partial volume of refuse;

FIG. 6 is a sectional view of the compactor showing the quick release cable hooks and shaft locking pin in place.

FIG. 7 is a fragmentary and enlarged sectional view of the quick release cable hook;

FIG. 8 is a fragmentary and enlarged sectional view of the winch shaft locked in position;

FIG. 9 is a fragmentary side view of an adapter bracket for mounting to trash containers which do not have handles of sufficient strength for supporting the cable tension loads;

FIG. 10 is a fragmentary side view of FIG. 9 showing the adapter bracket attached to the side of the trash container.

DESCRIPTION OF THE PRESENT EMBODIMENTS

Referring to FIG. 1, the compactor, generally referred to as 10, includes a subassembly which contains the base plate 11, the base plate supports 12, the vertical post 13, and the horizontal tube handle 14. Within the horizontal tube handle 14, the winch assembly generally referred to as 24, is positioned by the extension of the free turning shaft 17 which is rotated by the crank handle 19, and joined by the crank arm 18 with a free turning fastener. Cables 20 are attached to each end of the shaft 17 by means of quick release hooks 22 and likewise are attached to the trash container handles 25 by commercially available quick release hooks 21. The shaft 17 is locked, after reaching a desired crushing force, by positioning locking pin 23 into the slot of horizontal tube handle 14. The foregoing components are made into their basic assemblies by any appropriate method which results in the most economical manufacturing process while maintaining strength and functionability.

Referring to FIG. 2, openings 15 provide venting for trapped air to escape during the compacting operation.

The complete compactor assembly 10 with the winch assembly 24 attached, shown in FIG. 4, provides a pressing force. In accordance with the hand force on crank handle 19, a mechanical advantage is established which results in a high crushing force at the base plate 11 against the refuse by the reaction of this force through cables 20 into the handles 25 of the trash container 27. The crushing force is maintained by backing the locking pin 23 into the notch of shaft 17 as shown in FIG. 6.

The compactor assembly 10 when used without the winch assembly 24 installed, is shown in FIG. 5 posi-

tioned within a standard trash container 27, for intermittent tamping of refuse. This is accomplished by grasping the horizontal tube handle 14 with both hands and tamping small quantities of trash without the aid of the winch assembly 24.

In FIG. 6 the winch assembly 24 is positioned within the horizontal tube handle 14 with locking pin 23 retained in the slot of the horizontal tube handle 14. The shaft 17 is slotted on both ends to permit the fastening of cable hooks 22.

In FIG. 7, quick release cable hook 22 may be removed by sliding laterally outward from the slot in shaft 17 in order to remove the winch assembly 24 when this assembly is not required.

In FIG. 8 the locking pin 23 is engaged in the slot of horizontal tube handle 14.

In FIG. 9 and FIG. 10 an adapter bracket 26 is provided for use in attaching the hook 21 when a trash container is not equipped with an appropriate handle of adequate strength.

While no specific types of materials and dimensions are mentioned above, it is to be noted that the lack of specific material reference is not to be construed as limiting my invention in any manner.

It is to be understood that the particular embodiments of this invention, as described above and shown in the drawing, are merely illustrative of, and not restrictive on, the broad invention and that I do not desire to be limited in my invention to the exact details of construction shown and described, for obvious modifications will occur to persons skilled in the art.

I claim as my invention:

1. A trash compactor for use with a trash container of a type having sides, a bottom and a rigidized peripheral top edge, said container being further pro-

vided with handles adjacent said top edge and fixed on laterally opposite sides of said container, said compactor comprising, in combination:

- 5 a compactor plate adapted for horizontal disposition and vertical movement within said container;
- 10 a post fixed to said plate and extending vertically therefrom;
- a handle carried by an end of said post remote from said plate and disposed laterally from said end, said handle being generally an elongated hollow tube;
- a shaft rotatably disposed within said handle and having ends extending laterally from each end of said handle;
- 15 a crank secured to one end of said shaft; and
- a pair of cables, one end of each of said cables being fixed to said laterally extending ends of such shaft to permit winding thereof about said shaft, free ends of said cables being adapted for connection to said handles of said container, whereby, the turning of said crank will cause movement of said plate and said compactor relative to said container, thus to compact material disposed in said container.

2. The invention according to claim 1, wherein said compactor plate being provided with air relief vents is secured to said vertical post for adaptability to said common trash containers.

3. The invention according to claim 1, wherein said shaft, said crank free ends of cables are combined and readily installed or removed as an integral unit by the release of said cable on the end of said shaft which is opposite said crank handle.

4. The invention according to claim 1, wherein said shaft is slotted to receive said free end of cable.
